UNITED STATES PATENT OFFICE.

DAVID MORGAN, OF ASHLAND, WISCONSIN.

PENCIL-BOX.

1,109,590.

Specification of Letters Patent.

Patented Sept. 1, 1914.

Application filed May 28, 1910. Serial No. 563,901.

To all whom it may concern:

Be it known that I, DAVID MORGAN, a citizen of the United States, residing at Ashland, in the county of Ashland and State of Wisconsin, have invented certain new and useful Improvements in Pencil-Boxes, of which the following is a specification.

The present invention relates to certain new and useful improvements in pencil boxes such as are commonly used by school children, and the object of the invention is the provision of a pencil box which is designed to be permanently attached to the school desk and which embodies novel features of construction whereby the same can be readily moved into either an open or a closed position as may be desired.

The invention further contemplates a pencil box which is simple and inexpensive in its construction, which can be readily applied to a school desk of the usual design, and which will form a convenient receptacle for pencils, pens, and other small articles.

With these and other objects in view, the invention consists in certain combinations and arrangements of the parts as will more fully appear as the description proceeds, the novel features thereof being pointed out in the appended claim.

For a full understanding of the invention, reference is to be had to the following description and accompanying drawing, in which:

Figure 1 is an end view of the upper portion of a school desk having the pencil box applied thereto. Fig. 2 is a horizontal sectional view on the line 2—2 of Fig. 1, the pencil box being shown in full lines as moved into a closed position, and in dotted lines as swung outwardly into an open position, and Fig. 3 is a vertical transverse sectional view on the line 3—3 of Fig. 1.

Corresponding and like parts are referred to in the following description and indicated in all the views of the drawing by the same reference characters.

Referring to the drawing, the numeral 1 designates the upper portion of a school desk which may be of any suitable type, the top of the said desk being shown as extending beyond the ends thereof at 2. The pencil box 3 is pivotally mounted upon the lower face of the projecting end 2 of the desk top so as to be readily moved either into an open or a closed position.

The pencil box 3 preferably has an elongated

formation as indicated upon the drawing, and one end thereof has an angle strip 4 applied thereto. One of the arms of this angle strip is rigidly secured to the end of the box while the other arm of the angle strip projects outwardly therefrom at the top of the box and forms an ear which is pivotally connected to the projecting portion 2 of the desk top in any suitable manner as by means of the screw 5. The box is designed to be swung about this screw 5 as a center and may either be moved inwardly against the end of the desk, as indicated in full lines in Fig. 2 so that the box is closed by the projecting portion 2 of the desk top, or swung outwardly, as indicated by dotted lines in Fig. 2, so that ready access may be had to the interior of the box for placing pencils therein or removing them therefrom. When the box is swung inwardly into a closed position, the swinging end thereof is received within an angular or Z-shaped bracket 6 which is pendent from the desk top. The lower end of this bracket is formed with a horizontal arm 6^a which extends under the pencil box so as to form a support for the same, while the upper end of the bracket is shown as formed with a plate 6^b which is secured to the desk top by some suitable fastening members such as the screws 7.

The swinging end of the pencil box is connected to the extremity of the horizontal arm 6^a by means of a pair of links 8 and 9 which are pivotally connected to each other. The outer link 9 is pivotally connected to the pencil box 3, while the inner link 8 is pivotally connected to the horizontal arm 6^a, and a stop 10 projects from the bottom of the pencil box for engagement with the outer link 9, as indicated in dotted lines in Fig. 2, to limit the outward movement of the pencil box and prevent the two links 8 and 9 from being brought into alinement with each other so as to produce a dead center. It will thus be obvious that a slight angle is always maintained between the two links 8 and 9 and that the pencil box can be quickly moved into a closed position without the necessity of first breaking a dead center such as would be produced if the two links were permitted to be brought into alinement with each other. The stop 10 also engages the horizontal arm 6^a when the pencil box is swung into a closed position and would coöperate with the said hor-

izontal arm to limit the inward swinging movement of the box should the said box not abut against the end of the desk as in the present instance. It will thus be obvious that the pencil box can be easily and quickly swung either into an open or closed position by merely grasping the same and moving it as desired and that when in a closed position, it is disposed entirely under the projecting end 2 of the desk top so as to be out of the way and protected from injury.

While I have described the pencil box as applied to the top of a school desk, it will be readily apparent that it can with equal facility be mounted upon the lower face of an overhanging support of any suitable character.

Having thus described the invention what I claim as new and desire to secure by Letters Patent, is:—

In a device of the character described the combination of an overhanging support, a box open at the top thereof and arranged under the overhanging support so as to be normally closed thereby, said box being located adjacent the free edge of the overhanging support and substantially parallel thereto, means for pivoting one end of the box to the lower face of the overhanging support so that when the box is swung out-

wardly away from the overhanging support it will be uncovered to admit of access being readily had to the interior thereof, a Z shaped bracket having one arm thereof secured to the lower face of the overhanging support and projecting downwardly therefrom, the other end of the bracket extending under the free end of the box so as to prevent sagging thereof when the box is swung inwardly into a closed position, a pair of pivoted link members connecting the lower arm of the Z shaped bracket to the bottom of the box to limit the outward swinging movement of the box and provide a support for the same when it is swung outwardly, and a stop pin projecting from the box and serving the double function of engaging one of the link members to prevent the two link members from being swung into alinement when the box is moved outwardly and also to engage the lower arm of the Z shaped bracket to limit the inward swinging movement of the box when it is swung under the overhanging support.

In testimony whereof I affix my signature in presence of two witnesses.

DAVID MORGAN.
